COMBINED SPOUT AND DIVERTOR VALVE FOR A SHOWER OR THE LIKE

Dennis Charles Arbon, Boughton-on-the-Water, England,
assignor to Walker Crosweller & Company Limited,
Cheltenham, England

Filed Apr. 24, 1972, Ser. No. 247,254

Claims priority, application Great Britain Oct. 23, 1971

Term of patent 14 years

Int. Cl. D23—01

U.S. Cl. D23—20

FIG. 1 is a perspective view taken from the front and top of a combined spout and divertor valve for a shower or the like embodying my new design;

FIG. 2 is a side elevational view thereof; and

FIG. 3 is a perspective view taken from the rear and bottom thereof.

I claim:

The ornamental design for a combined spout and divertor valve for a shower or the like, as shown.
